CLAIM

We claim the ornamental design for an ear phone, substantially as shown and described.

DESCRIPTION

FIG. 1 is a perspective view of an ear phone assembly in accordance with the present design;

FIG. 2 is a perspective view of a second embodiment of an ear phone drawn without the cord for purposes of illustration, the only difference being the color;

FIG. 3 is a left side view of the ear phone shown in FIG. 2, the cord is drawn broken away for purposes of illustration;

FIG. 4 is a right side view of the ear phone shown in FIG. 3;

FIG. 5 is a top view of the ear phone of FIG. 1;

FIG. 6 is a bottom view of the ear phone shown in FIG. 5;

FIG. 7 is a front view of the ear phone shown in FIG. 1; and,

FIG. 8 is a rear view of the ear phone shown in FIG. 1.
